UNITED STATES PATENT OFFICE.

AXEL A. STROM, OF AUSTIN, ASSIGNOR TO THE STROM MANUFACTURING COMPANY, OF CHICAGO, ILLINOIS.

RAILWAY-FROG.

SPECIFICATION forming part of Letters Patent No. 416,691, dated December 3, 1889.

Application filed August 22, 1889. Serial No. 321,632. (No model.)

To all whom it may concern:

Be it known that I, AXEL A. STROM, a citizen of the United States, residing at Austin, in the county of Cook and State of Illinois, 5 have invented a new and useful Improvement in Railway-Frogs, of which the following is a specification.

My invention relates to an improvement in the class of railway-frogs in which clamps 10 are employed to embrace them across their bases and thus secure the parts together.

The object of my improvement is to provide simple, inexpensive, and readily and effectively adjustable means for securing the 15 clamps against displacement when they are wedged into place on the frog.

In the accompanying drawings, Figure 1 is a horizontal section taken below the heads of the rails of a railway-frog provided with my 20 improvement, with parts broken away to display details of construction; Fig. 2, a similar view of a portion of the same, illustrating a modification; and Fig. 3 is a section taken on the line 3 of Fig. 1, viewed in the direction of 25 the arrow and enlarged.

A A denote the wing-rails; B B, the point-rails, and C denotes the filling or other means of intermediate bracing.

D and D' are the clamps, involving any 30 suitable construction, but preferably that shown and embracing the frog across the base thereof, respectively near the extremities of its wider and tapering portions, being wedged into place to hold the parts together 35 by driving the clamps in the direction of enlargement of the frog. When with use the parts of the frog become loosened, they are tightened by driving the clamps farther toward the enlarged end. In any of the positions of the clamps to which they are 40 adjusted they require to be securely held against displacement by slipping, and this I accomplish, broadly stated, by securing or tying each independently of the other and by a 45 separate connecting medium to the frog. The means I employ for the purpose, and which I consider to be most advantageous, because in all respects desirable, comprise rods E, each bent toward one end substantially into

an S shape and straight toward its opposite 50 end, where it is screw-threaded, as shown at x, to receive a nut r. A rod E is inserted at its bent end into a hole provided to admit it in a wing-rail, (and preferably through the web portion thereof, as shown,) wherein, after 55 its insertion, (first, owing to the shape of the bend, with the rod extending perpendicularly to the rail, and afterward by turning it parallel therewith,) it is extended at its threaded end through an opening in the adjacent portion of a clamp, one such rod being provided for each clamp at one side of the frog, as shown, or at each side thereof, as desired. The threaded portion of each rod E thus projects part way or quite through the opening 60 in the respective clamp for which it is provided, and which is held against slipping in the direction of convergence of the sides of the frog by means of the nuts r. The nuts may be adjusted for their purpose either at 65 the outer sides of the clamps on the projecting threaded extremities of the rods E, as shown in Fig. 1, or at the inner sides of the clamps, as shown in Fig. 2, the manner of adjustment first named requiring the threaded ends of the rods to extend in the direction of convergence of the sides of the frog, and that last named requiring them to extend in 70 the opposite direction.

Whenever loosening of the parts of the 80 frog requires the clamps to tighten such parts, to be readjusted by further wedging or driving them in the direction of divergence of the wing-rails, this operation may be performed without manipulating the clamp-retaining means, which, after the readjustment, are screwed on the rods against the 85 clamps to present them, in their new positions, stops against their displacement.

What I claim as new, and desire to secure by 90 Letters Patent, is—

1. In a railway-frog, the combination, with the wing-rails A and point-rails B, of clamps D and D', embracing the frog across its base and adjustable lengthwise thereof, and secured each independently of the other and by a separate connecting medium, substantially 95 as described, to the frog against dis-

placement in the direction of convergence of the wing-rails, substantially as and for the purpose set forth.

2. In a railway-frog, the combination, with the wing-rails A and point-rails B, of clamps D and D', embracing the frog across its base and adjustable thereon lengthwise of the frog, and each secured to the frog independently of the other and by a separate connecting medium operating against the side of its respective clamp nearest the converging end of the frog to hold the clamp against slipping, and whereby the clamp may be tightened by driving it toward the diverging end of the frog without obstruction by the said connecting medium, substantially as described.

3. In a railway-frog, the combination, with the wing-rails A and point-rails B, of perforated clamps D and D', adjustably embracing the frog across its base, rods E, each secured at one end to a wing-rail and threaded to-

ward its opposite end and extending at its threaded end through the perforation of the adjacent clamp, and a nut *r* on the threaded end of each rod, substantially as and for the purpose set forth.

4. In a railway-frog, the combination, with the wing-rails A and point-rails B, of perforated clamps D and D', adjustably embracing the frog across its base, rods E, each bent, substantially as described, at one end and threaded toward the opposite end and inserted at its bent end through an opening in a wing-rail, and extending at its threaded end through the perforation in the respectively-adjacent clamp, and a nut *r* on the threaded end of each rod, substantially as and for the purpose set forth.

AXEL A. STROM.
